CONVERTIBLE VEHICLE TOP OR SIMILAR ARTICLE

Ralph C. Young and Richard T. Bingman, both of El Paso County, Colo., assignors to White Manufacturing Company, a corporation of Illinois

Filed Oct. 25, 1961, Ser. No. 67,251

Term of patent 14 years

(Cl. D14—27)

The side of the top not shown is a mirror image of the side shown.

We claim:

The ornamental design for a convertible vehicle top or similar article, as shown and described.
